COMBINATION OF A GARMENT CONTAINER
AND A GARMENT SUSPENSION MEANS

Irving Richer, Montreal, Quebec, Canada

Application June 28, 1956, Serial No. 594,476

5 Claims. (Cl. 205—7)

The invention relates to the combination of a garment container and suspension means as described in the present specification and illustrated in the accompanying drawings that form a part of the same.

The invention consists essentially of the novel features of construction as pointed out broadly and specifically in the claims for novelty following an explanation in detail of acceptable forms of the invention.

The objects of the invention are to device a container that will hold clothing throughout shipment or during storage such a manner that the clothing will require no pressing and may be transferred from the box directly to racks for display and sale or may be worn immediately by the wearer; to furnish a means for suspending articles such as clothing within the container; to facilitate the handling and shipping of garments with a minimum of folding or wrinkling of the same; to avoid garments from becoming badly creased, soiled or damaged through improper packing of the same in containers; to construct containers of the collapsed type for the purpose of shipment or storage and which will take little room and are easily assembled when required and may be used repeatedly; and generally to provide a container that will be durable in construction economical to manufacture and attractive in appearance and efficient in its use.

A more specific object of the present invention is the provision of the combination of a container and a separate suspension unit for suspending articles such as clothing within the container, said separate suspension unit being insertable through a slit provided in the roof of the container, both said container and suspension unit being made of fibrous material and so arranged that the roof of the container will serve as a reinforcement for the suspension unit to better support the articles hung from said unit.

Still another important object of the present invention is the provision of a suspension unit arranged to be supported in a container, said unit although being made of fibrous material being rigid in both transverse directions relative to its long axis so that it will not collapse under transverse forces exerted on the same.

In the drawings:

Figure 1 is a perspective view of the container in its open position for the reception of the garments to be suspended and illustrating the suspension unit in assembled position.

Figure 2 is a plan view of the blank for the container as illustrated in Figure 1.

Figure 3 is a fragmentary longitudinal sectional view as taken along the line 3—3 in Figure 1.

Figure 4 is a perspective view of the garment suspension unit.

Figure 5 is a plan view of the blank for the suspension unit.

Figure 6 is a perspective of the blank of the suspension member in partly erected position. Fig. 7 is a cross-section of the blank along line 7—7 of Fig. 6; Fig. 8 is an end perspective view of the blank at a further stage

of its erection; Fig. 9 is a partial perspective view of the completely erected blank to form the suspension unit; Fig. 10 is a plan view of a modified form of the blank for the suspension unit; and Fig. 11 is an end view of the erected blank of Figure 10.

Referring now more particularly to the drawings in which like reference characters indicate like elements throughout, the container itself is generally indicated by the reference numeral 1 and is preferably made from a single blank of fibrous material such as fiber board, and has any suitable box-like shape for storage of garments supported by hangers. The container 1 has opposed side walls 2, a bottom wall 3 and a top wall or roof 4, the container further has a closure front generally indicated at 5 and provided by foldable flaps 6 and 7. The roof 4 is provided with a transverse slit 8 which extends entirely across said roof 4 and communicates with aligned short slits 9 made in the adjacent portions of the side walls 2. The slits 8 and 9 are disposed in a common plane when the blank is folded into erected position.

The slit 8, 9 is adapted to removably receive a suspension unit generally indicated at 10. The suspension unit consists of a one-piece blank of elongated shape as shown in Fig. 5. This blank is provided with a centre crease line 11 extending longitudinally of the blank and with two additional crease lines 12 on each side of the centre line 11 and equally spaced therefrom; the blank further has two transverse crease lines 13 near the ends thereof which extend at substantially right angles to the crease lines 11 and 12. The portion of the blank extending between the transverse crease lines 13 form two central rib portions 14 joined together by the central crease line 11 and defined by said crease line 11 and the crease lines 12. This portion of the blank further defines two outer flanges 15 connected to the central portions 14 by the crease line 12.

The transverse crease lines 13 defines flaps 16 and 17 which depend from the central rib portions 14 and outer flanges 15 respectively and which are separate from each other along lines 18 in alignment with the crease lines 11 and 12.

The blank just described for the suspension unit is folded into erected position in the manner shown in Figs. 6 to 9 inclusive. The central rib portions 14 are folded one against the other along the common central crease line 11 to define a rib the two layers of which may be stapled or taped together although, the slit 8, 9 in the roof 4 is generally sufficient to hold them together. The outer flanges 15 are folded downwardly at right-angles to the rib portions 14 about the crease lines 12 so that the erected suspension member has a final T-shaped cross-section providing a transverse leg formed by the outer flanges 15 in alignment with each other in a common plane, and providing a main leg formed of a double layer of fibrous material. The flaps 16 depending from the rib portions 14 are folded outwardly at right-angles to said rib portions while the flaps 17 are folded downwardly over the flaps 16 and are secured thereto by means of staples 20 or the like. The overlapping flaps 16 and 17 plus the edges of the slit 8, 9 maintain the blank in its erected final position and also provide abutment members to prevent axial displacement of the suspension unit 10 with respect to the container 1 when the member 10 is assembled with the container 1.

The erected suspension unit 10 is inserted through the slit 8, 9 with the central rib formed by the centre portions 14 engaging through said slit 8, 9 and with the outer flanges 15 resting over and contacting the roof 4 on each side of the slit 8, 9. The flaring end flanges 1 formed by the overlapping flaps 17 and 16 engage the outside face of the respective side walls 2 of the container 1. The centre portions 14 of the suspension unit are

provided with a plurality of spaced holes 21 and/or slots 22 adapted to register with each other when said portions 14 are folded one against the other, for receiving the hook of a garment hanger A as shown in Fig. 3. The slots 22 and/or holes 21 permit adjustable spacing of the several garment hangers A in accordance with the various thicknesses of the garments suspended from said hangers.

The suspension unit 10 may be stapled to the side walls 2, but in practice this was found unnecessary because the weight of the garments suspended from the unit 10 is sufficient to maintain said unit 10 in proper position. Although shown as having an elongated shape, the unit 10 may vary in length to suit the dimensions of the container. Thus the blank for the unit 10 may be square or even wider than long.

It will be noted that due to its T-shaped cross section, the unit 10 will effectively resist transverse forces exerted on the same. Furthermore, due to the double layer construction of its main leg, plus the rigidity maintained by the stapled overlapping end flaps it has been found that the unit is capable, even when made entirely of cardboard, of supporting a plurality of relatively heavy garments without any necessity for the insertion of metal or wooden bars between its two rib portions 14. Moreover, the fact that the end flaps 16, 17 engage the outer faces of the side walls 2, positively prevents any axial displacement of the unit relative to the container 1. Finally it will be seen that because the flanges 15 abut and rest on the roof or top wall 4 said top wall serves as a reinforcement for the suspension unit.

In the above description, it is seen that the suspension unit, according to the present invention, is actually supported by the side walls of the container, the rib of the unit engaging the slits 9 opening at the top edges of the side walls 2 and the outer flanges 15 of the unit resting on said top edges. Thus, although it has been stated hereinabove that the top wall 4 serves as a reinforcement for the suspension unit, said reinforcement is not essential.

Figs. 10 and 11 show a modified form of the suspension unit. The blank for unit 10' is shown in Fig. 10 and is provided in the middle thereof with narrow strips 24 united together by a longitudinal centre crease line 25 and united to the central rib portions 14' by the longitudinal crease lines 26.

As in the unit 10, the central rib portions 14' are united to the outer flanges 15' by the longitudinal crease lines 12'.

The transverse crease lines 13' define flaps 16' and 17' which depend from the rib portions 14' and outer flanges 15' respectively and which are separate from each other along lines 18' in alignment with the crease lines 12'. No flaps depend from the strips 24. Holes 21' and slots 22' are made in the rib portions 14'.

The unit 10' is folded in the manner described for unit 10 and with the strips 24 folded inwardly to provide a reinforcement of inverted U-shaped cross-section and disposed between the overlapping rib portions 14'. The hooks of garment hangers 4 are inserted through the registering holes 21' and/or slots 22' over the reinforcement as shown in Fig. 11.

While preferred embodiments in accordance with the present invention have been illustrated and described it is understood that various modifications may be resorted to without departing from the spirit and scope of the appended claims.

What I claim is:

1. The combination of a container and suspension unit, said container and suspension unit being both made of fibrous material, said container having two opposite side walls each provided with a downwardly directed slit opening at the upper edges of said side walls, the bottom end of each slit being at a lower level than the open end thereof, said suspension unit consisting of an elongated, separate member disposed across said container and providing a vertical main leg inserted through said slits and

projecting beyond the outer faces of said slit side walls and a horizontal cross leg resting on and overlying said upper edges adjacent said slits, said unit further including integral end flanges at both ends thereof, arranged at

5 substantially right-angles to said main leg and said cross leg and disposed adjacent to and exteriorly of said slit side walls, said end flanges consisting of end flaps depending from said main leg and said cross leg, the end flaps of said cross leg at each end thereof overlapping and secured with the end flaps of said main leg at each end thereof, said overlapping and secured end flaps defining said end flanges, said end flanges maintaining said cross leg at substantially right-angles to said main leg, said main leg being further provided with spaced apertures made therethrough for the introduction of garment hangers, said unit so constructed and arranged that it has rigidity in a plane at right-angles to said main leg and in the plane of said main leg, and a load applied to said main leg will be transferred to said cross leg and distributed over a substantial portion of the upper edges of the side walls of said container.

2. The combination of a container and a suspension unit, said container and said suspension unit being made of fibrous material, said container having two opposite side walls provided with aligned vertical slits made in the upper portions of said side walls and opening at the upper edges thereof, said suspension unit consisting of a one-piece folded blank having a T-shaped cross-section with the vertical main leg of said unit inserted within said slits and projecting beyond the outer faces of said side walls, and the horizontal cross leg of said T-shaped unit overlying and resting on said upper edges adjacent said slits, said suspension unit further having integral, end flaps depending from said main leg and said cross leg, 30 the end flaps of said cross leg at each end thereof overlapping the end flaps of said main leg at each end thereof, said overlapping end flaps secured together to define end portions extending at substantially right-angles to the planes of said main leg and said cross leg and disposed adjacent to and exteriorly of the slit side walls of said container, said secured end portions maintaining said horizontal cross leg at substantially right-angles to said vertical main leg, said main leg further having spaced apertures made therethrough for the insertion of garment hangers for supporting garments, said unit having rigidity in a plane at right-angles to said main leg and in the plane of said main leg, and a load applied to said main leg will be transferred to said cross leg and distributed over a substantial portion of the upper edges of the side walls of said container.

3. The combination of a container and of a garment suspension unit removable therefrom, said container and unit being both made of fibreboard material, said suspension unit comprising a one-piece folded blank defining two central, elongated rib portions overlapping each other and joined to each other along a longitudinal edge thereof, each central rib portion having united therewith along a crease line parallel to the joined edge of said central rib portions, a flat outer flange extending outwardly at substantially right-angles to said central rib portion, said unit further having end flaps depending from both ends of said outer flanges and rib portions, the end flaps of each central rib portion extending outwardly at substantially right-angles thereto and the end flaps of the 50 united outer flange extending downwardly at substantially right-angles to said outer flange, the end flaps of each outer flange and united rib portion at each end thereof applied one against the other and rigidly interconnected, said interconnected end flaps maintaining each outer flange at substantially right-angles to the united rib portion, said rib portions having spaced registering apertures for the insertion of garment hangers for supporting garments, said container having opposite, upright side walls with aligned vertical slits made in said side walls at the upper marginal portions thereof and opening at the upper

edges of said side walls, said rib portions of said suspension unit removably inserted through and projecting beyond said slits, said outer flanges of said unit overlying and resting on the upper edges of said side walls adjacent said slits, and said end flaps of said unit disposed adjacent to an exteriorly of the side walls of said container on the sides of said slits, so constructed and arranged that the weight of the garment suspended from said rib portions will be transferred to said outer flanges and distributed over a substantial portion of the upper edges of said side walls.

4. The combination as claimed in claim 3, wherein said central rib portions are joined to each other along a longitudinal edge thereof by means of a strip of inverted U-shaped cross-section which is integrally interconnected with the said longitudinal edges of said central rib portions, and is disposed between said rib portions.

5. The combination of a container and a garment suspension unit removable therefrom, said container and unit being both made of fibreboard material, said suspension unit comprising a one-piece folded blank defining two, central, elongated rib portions overlapping each other and joined to each other along a longitudinal edge thereof by means of a common crease line, each central rib portion having united therewith along a second crease line parallel with said common crease line, a flat outer flange extending outwardly at substantially right-angles to said central rib portion, said unit further having end flaps depending from both ends of said outer flanges and rib portions, the end flaps of each central rib portion ex-

tending outwardly at substantially right-angles thereto and the end flaps of the united outer flange extending downwardly at substantially right-angles to said outer flange, the end flaps of each outer flange and united rib portion at each end thereof applied one against the other and rigidly interconnected, said interconnected end flaps maintaining each outer flange at substantially right angles to the united rib portion, said rib portions having spaced registering apertures for the insertion of garment hangers 10 for supporting garments, said container having opposite upright side walls with aligned vertical slits made in said side walls at the upper marginal portions thereof and opening at the upper edges of said side walls, said rib portions of said suspension unit removably inserted 15 through and projecting beyond said slits, said outer flanges of said unit overlying and resting on the upper edges of said side walls adjacent said slits, and said end flaps of said unit disposed adjacent to and exteriorly of the side walls of said container on the sides of said slits, 20 so constructed and arranged that the weight of the garments suspended from said rib portions will be transferred to said outer flanges and distributed over a substantial portion of the upper edges of said side walls.
